ABSTRACT

An electrical connector includes: a substrate having plural holes; plural contacts mounted in the corresponding holes, the plural contacts including a first row of contacts arranged as a pair of signal contacts flanked by two ground contacts, a second row of contacts having four ground contacts on one side of the first row of contacts, and a third row of contacts having four ground contacts on another side, each contact including a body and an upper arm; and a coupling element interconnecting the two ground contacts of the first row to selected ground contacts of the second and third rows, wherein the upper arm of each of the plurality of contacts has a contacting convex facing upward, and the four ground contacts of the second row are connected side by side and the four ground contacts of the third row are connected side by side.

**ELECTRICAL CONNECTOR HAVING
THREE ROWS OF CONTACTS AND A
COUPLING ELEMENT INTERCONNECTING
SELECTED GROUND CONTACTS THEREOF**

BACKGROUND OF THE INVENTION

1. Field of the Invention

The present invention relates to an electrical connector, comprising: a substrate having a plurality of holes; a plurality of contacts mounted in corresponding holes of the substrate, the plurality of contacts including a first row of contacts arranged as a pair of signal contacts flanked by two ground contacts, a second row of contacts having four ground contacts on one side of the first row of contacts, and a third row of contacts having four ground contacts on another side of the first row of contacts, each contact including a body, an upper arm, and a lower arm; and a coupling element interconnecting the two ground contacts of the first row to selected ground contacts of the second and third rows.

2. Description of Related Arts

U.S. Pat. No. 11,108,183 discloses an electrical connector having plural rows of contacts, wherein for any given two adjacent signal contacts serving as a differential pair with surrounding ground contacts, there may exist resonance frequency problem difficult to solve and introducing cross-talk.

U.S. Pat. No. 9,166,343 discloses an electrical connector having a ground lattice that includes longitudinal receptacle ground shields and lateral receptacle ground shields. The longitudinal receptacle ground shields are mechanically and electrically connected to the lateral receptacle ground shields. The ground lattice provides electrical shielding for contacts arranged in differential signal pairs. The ground lattice forms shield boxes with a pair of longitudinal receptacle ground shields on respective opposite sides of the corresponding shield box and with a pair of lateral receptacle ground shields on respective opposite sides of the corresponding shield box.

SUMMARY OF THE INVENTION

An electrical connector comprises: a substrate having a plurality of holes; a plurality of contacts mounted in corresponding holes of the substrate, the plurality of contacts including a first row of contacts arranged as a pair of signal contacts flanked by two ground contacts, a second row of contacts having four ground contacts on one side of the first row of contacts, and a third row of contacts having four ground contacts on another side of the first row of contacts, each of the plurality of contacts including a body and an upper arm; and a coupling element interconnecting the two ground contacts of the first row to selected ground contacts of the second and third rows, wherein the upper arm of each of the plurality of contacts has a contacting convex facing upward, and the four ground contacts of the second row are connected side by side and the four ground contacts of the third row are connected side by side.

BRIEF DESCRIPTION OF THE DRAWING

FIG. 1 is a perspective view of an electrical connector in accordance with the present invention;

2

FIG. 2 is an exploded view of the electrical connector; FIG. 3 is a view similar to FIG. 2 but from another perspective;

FIG. 4 is a top view of the electrical connector; FIG. 5 is a top view showing three rows of contacts of the electrical connector;

FIG. 6 is a perspective view of the three rows of contacts;

FIG. 7 is a view similar to FIG. 6 but from another perspective;

FIG. 8 is an exploded view showing selected ground contacts of the three rows of contacts;

FIG. 9 is a cross-sectional view of the electrical connector taken along line A-A in FIG. 4;

FIG. 10 is an exploded view of a varied electrical connector in accordance with the present invention;

FIG. 11 is a perspective view showing three rows of contacts and a coupling element of the varied electrical connector; and

FIG. 12 is an exploded view showing selected ground contacts of the three rows of contacts in FIG. 11.

DETAILED DESCRIPTION OF THE
PREFERRED EMBODIMENTS

25 Referring to FIGS. 1-9, an electrical connector 100 includes: a substrate 10 having a plurality of holes 13 through two opposite surfaces 11 and 12 thereof; a plurality of contacts 20 mounted in corresponding holes 13 of the substrate 10; and a coupling element 30 interconnecting the

30 two ground contacts 22a of the first row to selected ground contacts 22b and 22c of the second and third rows. As an example, the plurality of contacts 20 may include a first row of contacts along direction X arranged as a pair of signal contacts 21 flanked by two ground contacts 22a, a second row of contacts along direction X having four ground contacts 22b on one side of the first row of contacts along direction Y as group 220b, and a third row of contacts along direction X having four ground contacts 22c on another side of the first row of contacts along direction Y as group 220c.

40 In this embodiment, respective four contacts of the first, second, and third rows are aligned along direction Y so that the pair of signal contacts 21 are surrounded by ten (10) ground contacts in the form of a shield box 200. It is noted that the shield box 200 in FIG. 4 shows only part of the

45 electrical connector 100. The electrical connector 100 may include over a thousand contacts constructed in a similar manner as the shield box 200 or by merely expanding or repeating the shield box 200 in a suitable manner. As can be understood, in constructing a connector with one thousand contacts, either the group 220b, the group 220c, or the ground contacts 22a and 22b and 22c interconnected by the coupling element 30 may be shared by adjacent shield boxes 200.

50 Referring to FIGS. 5 and 8, each of the ground contacts 22b and 22c includes a body 221b or 221c, an upper arm 222b or 222c, and a lower arm. The upper arm 222b or 222c has a contacting convex 223 facing upward. The body 221b or 221c has a slot 2210b or 2210c. The coupling element 30 engages the slots 2210b and 2210c of the bodies 221b and 221c. In conjunction with FIG. 9, the ground contact 22a includes a body 221a, a first branch 222a engaging the slot 2210b of a corresponding ground contact 22b of the second row, and a second branch 223a engaging the slot 2210c of a corresponding ground contact 22c of the third row, the first

55 and second branches 222a and 223a constituting the coupling element 30 or a strip of the coupling element 30. The coupling element 30 is integrally formed with the ground

contact 22a. In this embodiment, both the ground contacts 22b and 22c have same structure and the bodies 221b and 221c thereof lie in a plane along the direction X. The body 221a of the ground contact 22a lie in a plane along the direction Y perpendicular to the direction X and the first and second branches 222a and 223a are coplanar with the body 221a.

Referring to FIGS. 5-8, each signal contact 21 has a body 211, an upper arm 212, and a lower arm. The upper arm 212 has a contacting convex facing upward. The four ground contacts 22b of the second row abut each other side by side or are otherwise connected together and the four ground contacts 22c of the third row abut each other side by side or are otherwise connected together so as to form a shielding structure. Preferably, the body 221b or 221c of each of the ground contacts 22b and 22c has a main part 224 and two opposite side parts 225. The slot 2210b or 2210c is formed at a junction between the main part 224 and the side part 225 and extends through a bottom thereof. As shown in FIGS. 1 and 2, the substrate 10 has receiving channels 14 through the surface 11 to accommodate the coupling element 30. After the coupling element 30 together with the ground contact 22a is mounted in place, the ground contacts 22b and 22c may be mounted to engage the coupling element 30 by way of the slots 2210b and 2210c.

Each of the ground contacts 22b and 22c may have a pair of symmetrically arranged connecting portions 226 connected with a contact carrier which is then severed.

Referring to FIGS. 10-12, an electrical connector 100 in a varied design in accordance with the present invention shows the ground contact 22a also has a body 221a with a slot 2210a and the coupling element 30 in the form of several strips interconnects corresponding ground contacts 22a, 22b, and 22c by way of slots 2210a, 2210b, and 2210c thereof. In this varied design, the ground contacts 22a, 22b, and 22c may have same structure. Namely, the body of the ground contact 22a in the first row lies in a plane along the direction X so that all ground contacts 22a, 22b, and 22c are oriented in same direction.

The invention claimed is:

1. An electrical connector comprising:
a substrate having a plurality of holes;
a plurality of contacts mounted in corresponding holes of
the substrate, the plurality of contacts including a first
row of contacts arranged as a pair of signal contacts

flanked by two ground contacts, a second row of contacts having four ground contacts on one side of the first row of contacts, and a third row of contacts having four ground contacts on another side of the first row of contacts, each of the plurality of contacts including a body and an upper arm; and

a coupling element interconnecting the two ground contacts of the first row to selected ground contacts of the second and third rows; wherein

the upper arm of each of the plurality of contacts has a contacting convex facing upward; and

the four ground contacts of the second row are connected side by side and the four ground contacts of the third row are connected side by side;

the coupling element includes:

a first strip interconnecting one of the two ground contacts of the first row to a corresponding ground contact of the second row and a corresponding ground contact of the third row; and

a second strip interconnecting the other of the two ground contacts of the first row to another corresponding ground contact of the second row and another corresponding ground contact of the third row;

the one ground contact of the first row has a first branch engaging the corresponding ground contact of the second row and a second branch engaging the corresponding ground contact of the third row, the first branch and the second branch constituting the first strip; and

the other ground contact of the first row has a first branch engaging the corresponding ground contact of the second row and a second branch engaging the corresponding ground contact of the third row, the first branch and the second branch constituting the second strip.

2. The electrical connector as claimed in claim 1, wherein the body of each ground contact in the first row lies in a plane along a first direction, and the body of each ground contact in the second and third rows lies in a plane along a second direction perpendicular to the first direction.
